Primary Examiner — Kimberly Barnes(74) *Attorney, Agent, or Firm* — Che-Yang Chen; Law Office of Michael Chen(57) **CLAIM**

The ornamental design for a cordless leaf blower, as shown and described.

DESCRIPTION

FIG. 1 is a perspective view of a cordless leaf blower showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 1;

FIG. 11 is a partial enlarged view of portion 11 in FIG. 2; and,

FIG. 12 is a partial enlarged view of portion 12 in FIG. 2. The broken lines shown in the drawings depict portions of the cordless leaf blower that form no part of the claimed design.

1 Claim, 12 Drawing Sheets(56)
